UNITED STATES PATENT OFFICE

RALPH F. SYMONDS, OF MARBLEHEAD, MASSACHUSETTS

TRAWL DOOR

Application filed December 26, 1925. Serial No. 77,811.

My invention relates to doors such as are used for keeping the mouth of a trawl net open while it is being towed, and is intended to provide a trawl door which, as compared with prior doors, will be stronger and more durable, will tow more easily, will be less liable to catch on obstructions, and will be reversible in the sense that it can be readily adapted for use either as the right-hand or 10 the left-hand door of a pair.

The features in which my invention resides are hereinafter described in connection with the accompanying drawings, in which—

Figure 1 is a front view of my door as 15 preferably constructed, the structural parts on the back of the door being shown in dotted lines;

Figure 2 is a transverse section on the line 2—2 in Figure 1; and

Figure 3 is a diagrammatic view on a smaller scale, illustrating a pair of the doors, with the net and the towing connections attached.

The door illustrated comprises a body portion 2 preferably made of sheet steel and provided on its back or outer face with a reinforcing structure riveted or otherwise secured thereto and including a pair of longitudinally-extending angle irons 3, located at a distance from the upper and lower edges of the 30 door, and diagonal angle irons 4 each extending from one end of one of the angle irons 3 to the adjacent corner of the door. Metal strips 5 bolted to the rearwardly-extending webs of the respective angle irons 3 and 4 serve to connect and stiffen the latter, and the door may be stiffened vertically by means of a pair of vertical angle irons 6 located at the ends of the angle irons 3. The lower edge of the door is provided with a sheet steel shoe 7 which is riveted or otherwise secured to one face of the door, preferably the front face, and extends downwardly and rearwardly therefrom so that it slants away from the direction of drag, as shown in Figure 2.

The towing bracket consists, in the construction illustrated, of a pair of bracket members 8 and 9, each of which has in general the form of a broad V with an eye at the angle of the V and has its free ends bent toward each other in the same straight line to

serve as pivots. The ends of the rear bracket member 8 are mounted in vertical bearings 10 located on the front face of the door at its longitudinal center and secured thereto by bolts or the like passing through the body portion 2 and the angle irons 3. The front bracket member 9 which acts as a strut, has its ends mounted in vertical bearings 11 secured to the door between its front edge and the bearings 10 in such position that the eyes in the two bracket members may be swung together and connected by means of a removable shackle 12, to which the towing cable 13 is attached.

The attachment of the net to the door is provided for by means of a pair of shackles 14 located respectively at the rear corners of the door and each mounted on a pin 15 which passes through the body portion 2 and the adjacent angle iron 4. The perforations 16 formed in the body portion 2 adjacent to its upper corners provide for the attachment of buffers such as are customarily used to protect the sides of the trawling vessel when the door is hauled in.

It will be observed that the door above described is symmetrical with respect to its ends, so that in order to make it reversible and thus enable it to be used either as a right-hand or a left-hand door it is necessary merely to shift the bearings for the bracket member 9 to the opposite side of the center bearings 10, and to this end the bearings 11 are made detachable and perforations are provided for the reception of the attaching bolts in either position of the bracket, a pair of these perforations being shown at 17. When the door is reversed it is of course necessary to shift the connections to the net also, and provision is made for doing this by forming a perforation 18 in the outer end of each angle iron to receive the pivot on which the corresponding shackle 12 is mounted.

Figure 3 shows a pair of the doors with a net, 19, and the two branches of the towing cable 13 attached to the brackets on the respective doors. While the net is being towed the towing strain is taken up by the reinforcing structure above described, to which the towing cable and the net are attached, and

the only substantial strain on the body portion is that due to the water pressure, of which the lateral component acts on the two doors to force the latter apart and thereby 5 keep the mouth of the net open. Because of its downward and rearward slant the shoe at the bottom of the door rides readily over ordinary obstacles and is not liable to dig into the sea bottom, so that the door tows more 10 easily than prior doors and its spreading action on the mouth of the net is less subject to disturbance by variations in the strains applied to the door. The shoe is also more durable than those heretofore employed because of 15 its greater area, over which the wear is distributed, and if necessary it can be removed and replaced by another.

In addition to the foregoing advantages, the construction is such that the entire body 20 of the door can be made of steel, resulting in much greater strength and durability than is possible in the case of the usual wooden door, and towing connections other than the form of bracket described may be readily substituted for the latter if desired. These characteristics, together with the reversibility of the door, substantially increase its utility as compared with prior doors, and it will be evident that the details of construction may 25 be modified in various ways without losing these advantages or departing from my invention as defined in the subjoined claims.

I claim:

1. A trawl door comprising a body portion 35 having provisions for attaching a net thereto at either of its ends, and towing connections located on the front face of the body portion, said connections being reversible with respect to the ends of the door.
2. A trawl door provided on its front face with a towing bracket comprising two members, one of which is pivoted on a vertical axis located at the longitudinal center of the door, and means for detachably pivoting the other 45 member to the door between either end of the latter and its longitudinal center, said bracket members being provided with means for attaching the towing cable to both of them when swung together.
3. A trawl door comprising a body portion, a reinforcing structure secured to its back face, a towing bracket located on the front face of the body portion and comprising two members each adapted to swing on a vertical 55 axis, bearings for one of said members located at the longitudinal center of the body portion and connected through the latter to the reinforcing structure, and bearings for the other member adapted to be detachably secured to the body portion between either end of the latter and its longitudinal center, said bracket members being provided with means for attaching the towing cable to both of them when 60 swung together.
4. A trawl door comprising a body portion,

a reinforcing structure secured to its back face, a towing bracket located on the front face of the body portion and connected through the latter to the reinforcing structure, said towing bracket being reversible with respect to the ends of the door, and provisions for attaching a net to the door at either of its ends. 70

5. A trawl door comprising a body portion, a reinforcing structure secured to its back face and extending to each of the four corners thereof, a towing bracket located on the front face of the body portion and connected through the latter to the reinforcing structure, said towing bracket being reversible with respect to the ends of the door, and provisions for attaching the net to the reinforcing structure at either of its ends. 75

6. A trawl door comprising a body portion, a reinforcing structure secured to its back face and including longitudinally-extending members located between the center line of the body portion and its upper and lower edges, respectively, and diagonal members diverging towards adjacent corners of the body portion, means for attaching a net to the diagonal members, and towing connections located on the front face of the body portion and attached directly to the longitudinal members of the reinforcing structure by connections passing through the body portion. 80 85 90

Signed at Boston, Massachusetts, this 21st day of December, 1925.
